PICTORIAL GAME APPARATUS

John Thomay, Columbus, Ohio

Application April 4, 1933, Serial No. 664,375

9 Claims. (Cl. 273—157)

This invention relates to improvements in game apparatus and more particularly to pictorial puzzles composed of a number of interfitting separable parts.

Among other objects, the invention aims to provide an improved puzzle of the type indicated embodying a game board or sheet formed of a plurality of openings, the portions of the board or sheet between the openings being provided with parts of a composite picture, while said openings are adapted to receive interfitting separable game pieces, which bear the balance of the complete picture, so that when the removable game pieces, which may be of regular or irregular outline, corresponding to the configuration of the openings in the game board, are all inserted and frictionally retained in their respective openings, one or more complete pictures will be presented on the extended planar surfaces of the apparatus.

The ordinary picture or jig saw puzzle now in general use comprises rectangular sheets composed of wood or cardboard having pictures printed, painted or otherwise affixed thereon, the sheet then being sawed, stamped or cut into a number of separable interfitting parts of irregular form which are adapted to be fitted together by the user in solving the puzzle, the user being assisted in the operation of bringing together the parts of the puzzle not only by the shape of the pieces but by the parts of the picture displayed thereon. Such a picture puzzle requires the associated employment of a base, table or other playing surface to effect the support of the separate pieces of the puzzle during the task of fitting the pieces together and to maintain such assembled order, a further care must be constantly exercised to prevent displacement of the interengaging pieces in order to avoid the undoing of completed effort in solving the puzzle through the accidental separation of the component pieces.

Therefore, the present invention provides a picture puzzle wherein the separable game pieces are frictionally gripped by and conform to the configuration of the walls or surfaces of the respective openings therefor formed in a stencil-like game board whereby to positively retain the game pieces in association with the game board so that the latter may be lifted, transferred from place to place, and otherwise moved without affecting the operative or assembled order of the removable parts retained in the game board, thus rendering the apparatus self-containing and substantially independent of other supporting means.

A further object of the invention resides in

providing the openings of the game board and the separable game pieces with tapered adjoining walls or surfaces so that a wedge-like relationship will be established when the game pieces are fitted into said openings, for the purpose of effecting the positive support and retention of the game pieces in association with the game board.

With these and other objects in view, which will appear as the description proceeds, the invention consists in the novel features of construction, combination of elements and arrangements of parts hereinafter fully described and pointed out in the appended claims.

In the accompanying drawing:

Fig. 1 is a plan view of game apparatus formed in accordance with the present invention;

Fig. 2 is a vertical sectional view taken on the plane indicated by the line 2—2 of Fig. 1;

Fig. 3 is a similar view of a slightly modified form of my invention;

Fig. 4 is a fragmentary plan view disclosing a further modification;

Fig. 5 is a sectional view on the line 5—5 of Fig. 4.

Referring more particularly to the drawing and to the form of my improved game apparatus depicted in Figs. 1 and 2 thereof, the numeral 1 designates the game board proper. This game board or sheet may be formed from any suitable material such as wood, cardboard, metal or composition materials which possess a fair degree of rigidity and resist flexing or bending of the board under ordinary conditions of use and handling. The board may be of rectangular configuration, as indicated, or of other desired marginal forms. In the manufacture of the game board, the sheet of material from which the latter is formed is stamped, punched, sawed or otherwise operated upon to produce a plurality of stencil-like openings as indicated at 2, and in the production of these openings separable game pieces 3 are likewise produced from the sheet from which the game board is formed which are adapted to be inserted, in the development of the puzzle, into said openings and to be positively retained thereby against accidental displacement. A complete picture 5 is preferably suitably affixed to one or more of the surfaces of the sheet from which the game board is formed prior to the formation of the openings 2 and the game pieces 3, so that when the latter are produced, they will each contain a fragment of the complete picture so that when the game pieces are again reinserted into their proper respective openings, the composite picture will be presented. Thus, the picture 5 may be pre-

sented to the upper or lower surfaces of the game board or to both of said surfaces, and this feature is made possible by reason of the fact that the game board is of uniform thickness throughout all portions thereof, and the upper and lower surfaces of the game pieces 3 correspond exactly with the complementary surfaces of the game board. It will be understood that the openings 2 may be of regular or irregular form. An irregular formation 10 has been illustrated in Fig. 1, but in the event a more difficult puzzle is desired, the game pieces may be of corresponding regular shapes so that the user of the apparatus will be required to insert the game pieces into proper openings by reliance 15 upon pictorial or color matching combinations.

It is one of the important features of the present invention that the game pieces shall fit relatively tightly in the openings 2, so that when this is done the entire game apparatus may be lifted 20 bodily and moved from point to point or otherwise moved or adjusted without the game pieces becoming loose and accidentally displaced from the openings in which they are received. This end is attained in the structure disclosed in Figs. 1 and 25 2 by the frictional engagement which exists between the adjacent walls of the game pieces and the openings 2. If desired, a variation of this, as shown in Fig. 3, resides in punching or otherwise producing the openings 2 so that the walls 6 there- 30 of will be substantially tapering toward the lower surface of the game board. The game pieces 3 are likewise provided with tapering walls matching the wall 6. By this arrangement, a wedge-like positioning of the game pieces in said openings takes place, by which a very effective positioning of the game pieces in said openings is secured and accidental displacement of the game pieces avoided. This construction, as disclosed in Fig. 2, eliminates the use of a base piece below the 35 opening 2 as suggested by the prior art.

A further modified form has been disclosed in Figs. 4 and 5, wherein the openings 2a are of regular or similar form and are provided with slits 7 by means of which a limited amount of resiliency 40 is imparted to the walls of said opening, enabling them to grip more firmly the game pieces 3a than is obtainable in the simple form of the invention illustrated in Fig. 2. In Fig. 5, there has been disclosed lithographed picture sheets 8 and 9, which 45 are applied to both the upper and lower surfaces of the game apparatus.

The present invention thus provides a pictorial game puzzle wherein the separable game pieces are securely fitted into correspondingly shaped 50 openings provided in a stencil-like game board, so that the game pieces may be securely retained in their inserted positions within said board and prevented from becoming accidentally displaced or otherwise unintentionally removed from association with the board. This enables the game to be handled with convenience in that it is practically self-contained, and does not require a supporting base or table upon which it must be placed in order to be played. I am aware of the fact that game devices have been suggested by the prior art wherein separable game pieces are fitted into correspondingly formed sockets or openings formed in a game board or sheet but desire to point out that my present invention distinguishes 60 from such prior structures by the fact that the game pieces are frictionally and securely retained in said openings and may be only removed by the application of positively applied pressure of sufficient force to displace the game pieces from their 70

frictional retention in association with the openings of the game board.

What is claimed is:

1. A picture puzzle comprising a playing board formed with a plurality of stencil-like openings therein, and separable game pieces conforming to the configuration of said openings and receivable therein, the adjoining surfaces of said openings and game pieces being frictionally engaged to positively retain said game pieces in said board independently of additional sources of support. 80

2. A picture puzzle comprising a game board provided with a plurality of openings extending transversely therethrough from one side to the other, separable game pieces conforming to the configuration of said openings and receivable therein, said game pieces being completely viewable from the top and bottom of said game board, and the interengaging surfaces of said game pieces and openings being sufficiently tight fitting to maintain the game pieces in said openings independently of additional means of support. 85

3. Game apparatus of the character set forth comprising a game board provided with a multiplicity of openings extending transversely therethrough from the top to the bottom, separable game pieces formed to be frictionally fitted in said openings and to completely occupy the same, whereby said game pieces may be completely viewable from the top or bottom of the game board and retained in connection with the latter without added means of support, and pictorial representations applied to said game board 100 and game pieces. 105

4. A pictorial puzzle comprising a game board formed with a multiplicity of irregularly shaped openings extending through the game board from the top to the bottom thereof, and separable game pieces conforming to the irregular configuration of said openings and frictionally inserted in the openings for retention in connection with the game board without added means of support. 115

5. A pictorial puzzle comprising a game board formed with a multiplicity of substantially uniformly shaped openings extending through the game board from the top to the bottom thereof, and separable game pieces conforming to the 120 configuration of said openings and frictionally inserted in the openings for retention in connection with the game board without added means of support.

6. Game apparatus of the character set forth comprising a game board provided with a plurality of spaced openings extending therethrough from top to bottom, said openings being provided with downwardly tapering walls, and a plurality of separable game pieces frictionally received 130 within said openings and having the outer surfaces thereof conforming to the tapered configuration of said opening walls. 135

7. Game apparatus of the character set forth comprising a game board provided with a multiplicity of spaced openings having downwardly tapering walls, and separable game pieces formed to be tightly received within said openings, said game pieces having outer walls conforming to the taper of the opening walls, whereby when 140 said game pieces are fully inserted in said openings, the top and bottom surfaces thereof lie substantially flush with the corresponding surfaces of the game board. 145

8. Game apparatus comprising a game board 150

formed to include a plurality of spaced openings extending through the board from the top to the bottom thereof, said openings being provided with relatively resilient margins, and separable 5 game pieces receivable within said openings and arranged to be frictionally engaged by the resilient margins of said openings, the top and bottom surfaces of said game pieces being arranged to register with the corresponding surfaces of the game board when said game pieces occupy 10 fully inserted positions in said openings.

9. A picture puzzle comprising a game board

formed from a single layer of suitable material, said board being provided with a plurality of openings extending therethrough and having the same contour when viewed from the back of the board as they do from the front, separable game pieces conforming to the configuration of said openings and receivable therein, and means formed with the edges of said opening to hold said pieces in their respective places regardless of the position of said board.
